E. BERLINER.
TELEPHONE SYSTEM.

No. 255,239.

Patented Mar. 21, 1882.

Geo. Willis Pierce
Joseph N. Connolly

Emile Berliner

UNITED STATES PATENT OFFICE.

EMILE BERLINER, OF BOSTON, MASSACHUSETTS.

TELEPHONE SYSTEM.

SPECIFICATION forming part of Letters Patent No. 255,239, dated March 21, 1882.

Application filed December 15, 1881. (No model.)

To all whom it may concern:

Be it known that I, EMILE BERLINER, of Boston, in the county of Suffolk and State of Massachusetts, have invented certain Improvements in Telephone Systems, of which the following is a specification.

This invention relates to certain arrangements and switching of circuits for cases where a telephone-transmitter is used alternately with a local battery and induction-coil, or with a line-battery and the coil excluded. Such a case may happen—for instance, when a subscriber to a telephone system of one city intends to speak to a person in another city, using the same and no special transmitter. It is well known that the induce-currents usually employed in telephone systems, though being cheap and very effective for ordinary inter-communication, are not efficient when the line which they traverse offers extraordinary resistance, or if there is bad insulation, giving cause for leakage on the line. In this case induced currents are more apt to diffuse themselves through leakage to the ground than a battery-current of ordinary tension would under the same conditions, and hence it becomes desirable in telephonic intercommunication over long or badly-insulated lines to employ a large line-battery instead of a small local battery to be worked upon by the transmitter. In my system this line-battery is stationed at the central office. The arrangements, therefore, broadly comprise a system of telephonic inter-communication in which the battery-transmitter of a subscriber to a system can readily be switched with the battery and induction-coil into a local primary circuit, and made to act upon a secondary circuit or into the line, to connect with a line-battery at the central office.

In the drawing, B is the central-office battery of one system, and N the central-office battery of another.

R and Q are subscribers' stations to the two respective systems.

A A are battery-transmitters; C C, batteries; T T, receiving-telephones.

I I are induction-coils with two sets of connections—viz., P P primaries, S S secondaries.

Y Y Z Z J J J J are switches, and E E are earth-plates.

In the ordinary intercommunication between subscriber R, for instance, and another subscriber of the same system, his switches Y and Z are set upon buttons or positions 2 2. The transmitter will then be in local circuit with battery C and primary coil-connections P P, while the telephone T is thrown through the secondary connections S S to line and ground. If, now, however, this same subscriber R wishes to speak to subscriber Q of system N, it may be found that the resistance of the line L, connecting the systems B and N, may be too large or its leakage too great to allow the secondary impulses of the respective transmitters to effectively reach the other receiving-telephone. In this case it will be found necessary to bring the transmitter on the line in direct circuit with the telephones and a line-battery, and to accomplish this promptly my arrangements of circuits and switches will be found very practicable. In this instance all the switches are set upon the buttons or positions marked 1. The central offices thereby switch a battery into the line, and the transmitters and receiving-telephones are now in one circuit passing through the central-office batteries.

What I claim is—

1. A subscriber's station of a telephone system consisting of the combination of a battery-transmitter, an induction-coil, a local battery, a receiving-telephone, and switch Z, substantially as described, and so arranged that the line-circuit can by means of this switch be directed either through the secondary coil or 85 through the transmitter to the ground.

2. A subscriber's station of a telephone system consisting of the combination of a battery-transmitter, an induction-coil, a local battery, a receiving-telephone, and switch Y, substantially as described, and so arranged that the transmitter-circuit can be directed by this switch either through the local battery or to the ground.

In testimony whereof I have signed my name 95 to this specification, in the presence of two subscribing witnesses, this 13th day of December, 1881.

EMILE BERLINER.

Witnesses:

J. H. CHEEVER,
GEO. WILLIS PIERCE.
